UNITED STATES PATENT OFFICE.

ARTHUR E. WOODRUFF, OF MOUNT CARMEL, CONNECTICUT, ASSIGNOR TO THE W. W. WOODRUFF & SONS CO., OF MOUNT CARMEL, CONNECTICUT.

DOOR LOCK.

Application filed April 25, 1922. Serial No. 556,517.

To all whom it may concern:

Be it known that I, ARTHUR E. WOODRUFF, a citizen of the United States, residing in Mount Carmel, county of New Haven, 5 and State of Connecticut, have invented certain new and useful Improvements in Door Locks, of which the following is a full, clear, and exact description.

My invention relates to door locks and 10 while the principles thereof may be more particularly applicable to vehicle doors, it will be understood that I do not confine myself entirely to locks of this type.

It is usual in the manufacture of door locks 15 for automobiles or other vehicles having closed bodies to provide means for locking the doors to prevent the entry of unauthorized persons into the vehicle. It is also common to provide what may be called 20 locking handles, or handles having locks mounted in the spindles thereof, which must be operated by the proper key before the handles may be turned to open the doors.

In the past it has been the custom to lock 25 the handle spindles or stems to the escutcheon plates, but a serious disadvantage in this method is that the escutcheon plate may be loosened or unscrewed readily and the handle may then be operated to open the door.

30 In other forms of vehicle locks the door must be locked by a key from the outside, after it has been closed, and it sometimes occurs that the owner of the vehicle neglects to lock the door after closing it and thus the vehicle is accessible for the entry of an unauthorized person.

One object of my invention is to overcome 35 the disadvantages above referred to and to provide a lock, the mechanism of which may be set to lock automatically when the door is closed, and also to provide a lock wherein the locking or dogging device will be located within the lock or within the outer surface of the door where it will not be 45 subject to easy attack.

Another object of my invention is to provide 40 a lock of this character with a dogging member which is located within the lock mechanism and which may be actuated by a

key operated lock mounted in the spindle of 50 the handle.

A still further object of my invention is to provide means to prevent the bolt from being withdrawn by the door handle, which means shall be entirely independent of the 55 escutcheon plate and to provide means for securing the handle in position in the lock which shall also be independent of the escutcheon plate in order that any tampering with or loosening of the escutcheon plate 60 will have no effect whatever toward overcoming the lock.

Another object of my invention is to provide 65 a vehicle door lock of very simple character and of improved operation.

To these and other ends the invention consists in the novel features and combinations of parts to be hereinafter described and claimed.

In the accompanying drawings: 70

Fig. 1 is an outside elevational view of a portion of a vehicle door with my improved lock mounted thereon;

Fig. 2 is an inside view of the same;

Fig. 3 is an edge view of the parts shown 75 in Figs. 1 and 2;

Fig. 4 is a sectional view on line 4—4 of Fig. 1;

Fig. 5 is a sectional view substantially on line 5—5 of Fig. 4 showing the lock mechanism in elevation; 80

Fig. 6 is a view similar to Fig. 5, but showing the dogging slide in operative position;

Fig. 7 is a view similar to Fig. 6, but showing the parts in the position occupied 85 just after the dogging slide has been moved by the key to inoperative position;

Fig. 8 is a view on line 8—8 of Fig. 4 showing the latch retracted by the handle;

Fig. 9 is a sectional view on line 9—9 of 90 Fig. 7;

Fig. 10 is a sectional view on line 10—10 of Fig. 5; and

Fig. 11 is a sectional view on line 11—11 of Fig. 10. 95

In the illustration of a preferred embodiment of my invention I have shown a portion of a vehicle door at 10 upon which is

mounted a lock embodying my improvements. The parts of the lock mechanism may be supported upon a supporting plate 11 having a face plate 12 adapted to be mounted at the edge of the door. Upon the plate 11 is slidably mounted a latch bolt 13 in a guide 14 and in an opening 15 in the plate 12. This bolt is provided with the usual beveled head 16 and is recessed at 17 rearwardly of the head for a purpose to be hereinafter described.

As a convenient means for urging the bolt to protracted position, I have shown a coil spring 18 having one end thereof seated in a slot 19 provided in a stud 20 secured to the plate 11. The free end of the spring is adapted to enter a recess 21 in the latch bolt and bear against the shoulder 22 at the forward end of this recess to retain the bolt in a normally protracted position.

The bolt retracting means in the form shown is a hub member 23 provided with a collar 24 journaled in an opening 25 in the plate 11 and a bolt actuating lever or finger 26 extending into the recess 17 and bearing against the shoulder 27 upon one side of the recess.

Slidably mounted between the guide lug 29 and the posts 30 on the plate 11 is a dogging member 31 upon which is provided a button 32 extending through a slot 33 in the plate 11 in position to be manually engaged from the inside of the door. The slide 31 is provided with a detent 33^a which is adapted to engage below a shoulder 34 provided upon the hub 23 to dog the hub against movement. The hub 23 and the slide 31 are retained in position by being clamped between the main supporting plate 11 and a smaller auxiliary plate 35, which may be secured by screws 36 to lugs or posts upon the main plate. The small plate 35 is provided with an opening 37 through which extends an offset finger 38 formed as an integral part of the slide 31. The opening 37 is elongated, as shown in Figs. 5 to 8 to permit the reciprocation of this slide.

The collar 24 of the hub 23 is provided with a square opening 39 in which is mounted a similarly shaped stem 40 which projects through the plate 11 upon the inside of the door and upon which is secured the inside operating handle 41 by means of the screw 42 and the bushing or collar 43. At the opposite end of the stem 40 is secured a shell 44 which extends through the door and upon which is loosely mounted the escutcheon plate 45 adapted to be secured to the outside of the door by screws or the like 46.

The outside knob 47 is provided with a hollow spindle 48 which is adapted to telescopically receive the end of the shell 44, the two members being secured together by

the pin 49. The spindle is provided at its inner end with an ornamental shoulder 50, which is adapted to abut against the outer edge of the escutcheon. Beyond this shoulder the spindle is formed with a slot 51 to receive the lug 52 upon the shell 44, which in addition to the pin 49 provides for the securing of these parts against relative rotation.

Within the spindle 48 is mounted a rotary pin tumbler lock 52^a consisting of a pin tumbler case 53 and a key barrel 54. To the inner end of the key barrel is secured a key rod 55, which extends into the shell 44 and which may have its end mounted in an aligning socket 56 in the end of the shell. Upon the key rod 55 which is preferably polygonal in shape is mounted an actuating cam 57 shown more especially in Figs. 5 to 7, which is adapted to turn in a slot 58 provided in the shell opposite the offset portion 38 of the dogging slide.

It will be apparent that in the assembling of the parts of the device, the lock 52^a, together with the key rod, may be mounted in the hollow spindle and thereafter the shell 44 may be connected to the spindle by telescoping the adjacent ends of these parts to some extent after the lug 52 has been aligned with the slot 51. The pin 49 is then passed through the parts and the escutcheon 45 may then be slipped over the end of the shell 44 in position to be secured to the door. The hollow spindle or shell 44 with the stem 40 extending therefrom is then passed through the opening in the door and the stem 40 inserted through the opening 39 in the hub member 23 when the plate 11 with the parts of the lock mechanism thereon has been mounted upon the door. The shell 44 and the hollow spindle member 48, being rigidly interconnected, form in effect a single spindle for operating the bolt from the outside of the door. It will be apparent that my lock is of simple construction and at the same time possesses many advantages of operation and may be assembled with ease and economy.

The operation of the improved lock will be more or less obvious from the foregoing description. It will be readily seen that when the parts are in the position shown in Fig. 5, the latch 13 can be retracted for opening the door by turning either the inside handle 41 or the outside knob or handle 47, both of which are connected through the square stem 40 to the latch retracting hub having the retracing lever or finger 26. When the driver of the car intends to leave it for some time at the curb or elsewhere, the door having been opened by manipulation of the inside handle 41, he can conveniently move the button 32 from the position shown in Fig. 2 to the opposite end of the slot 33, thus moving the dogging slide 31

from the position shown in Fig. 5 to the dogging position shown in Fig. 6, wherein the detent 33^a is moved below the shoulder to dog the hub 23 against movement. The door can be then closed as the bolt can be freely pushed in by contact with the strike plate in which operation the bolt is pressed back against the action of its spring away from the operating lever or finger 26, which

remains in the locked position. When the door has been closed, it will obviously be impossible to open it from the outside by manipulation of the outside handle, which cannot be turned without previous actuation of the key mechanism. When the owner or driver returns to the car and desires to open the door, he inserts the proper key into the key hole 59 and turns the key barrel 54 so as to rotate the key rod 55 and the actuating cam 57, which in the locked position abuts the offset finger 38 of the dogging slide, as shown in Fig. 6. The cam, acting upon the offset finger 38 and being turned in the proper direction by the key, moves the slide rearwardly to its inoperative position shown in Fig. 7 so as to release the hub and permit the same to be turned by manipulation of the outer handle, as shown in Fig. 8.

It will thus be seen that the operation of locking the door can be carried out with maximum convenience from the inside of the car after the door has been opened by merely shifting a small button or the like

and then closing the door, after which the use of the key is a necessary incident to the opening of the door from the outside, as described. By having the key controlled locking mechanism act on the hub rather than on the bolt itself, the door may be readily closed without injury after the dogging mechanism has been set in the operative position, while the bolt is not retractable from the outside after the door has been closed except after previous use of the proper key.

If an unauthorized person attempts to attack the lock by loosening the screws 46, it will be apparent that the escutcheon plate 50 will rotate freely upon the shell 44 and the spindle 48 will not be loosened or affected in any way. While the bolt is not dogged against retraction by contact with the strike, the operating hub is dogged 55 against movement by the slide which is located within the door and which may not be successfully attacked unless access is had to the lock mechanism itself.

It will be apparent, therefore, that the improved lock combines great security against attack with maximum facility of operation, although the construction is relatively simple and inexpensive when the functions thereof are taken into account.

While I have shown the lock as equipped

with a dogging mechanism having a rotary pin tumbler lock to release the same from the outside, I desire to have it understood that I do not limit myself in all aspects of the invention to the employment of the pin tumbler lock, nor do I limit myself in all cases to the employment of a key operated lock housed within the outer knob or handle.

While I have shown and described a preferred embodiment of my invention, it will be understood that the principles thereof are not limited to the exact details shown, which are capable of modification and variation within the spirit of the invention and the scope of the appended claims.

What I claim is:

1. In a door lock, a bolt, manually operable means projecting from the door for withdrawing the bolt, means manually movable into engagement with said operable means for dogging said means against movement while allowing the retraction of said bolt, and key controlled means carried by said manually operable means for rendering said dogging means inoperative.

2. In a door lock, a bolt, a bolt retracting spindle projecting from the door, dogging means manually movable into position to prevent the operation of the bolt retracting spindle, but permitting the bolt to operate, and key controlled means carried by the spindle to move said dogging means to inoperative position.

3. In a door lock, a bolt, a bolt operating spindle projecting from the outside of the door, means movable from the inside of the door to operative position whereby the operating spindle is dogged, but the bolt is free to operate, and key controlled means carried by the spindle to positively move said dogging means into an inoperative position.

4. In a door lock, bolt supporting means, a bolt and a dogging member carried by said supporting means, a bolt operating member projecting from the outside of the door, said dogging member being arranged to dog the same independently of the bolt, and key controlled means carried by said operating member to render said dogging means inoperative.

5. In a door lock, a bolt, bolt operating mechanism including a member projecting from the outside of the door, dogging means manually movable into the path of said operating mechanism to dog the same without dogging the bolt, and means carried by the projecting means to move the dogging means out of the path of said operating mechanism.

6. In a door lock, a bolt, bolt retracting means, dogging means within the door manually movable to position to prevent operation of the retracting means but al-

- lowing operation of the bolt and key controlled means carried by said retracting means to move the dogging means to inoperative position.
- 5 7. In a door lock, a bolt, bolt retracting means, means within the door manually movable into engagement with said bolt retracting means to dog the retracting means against movement while permitting the bolt 10 to operate, and key controlled means carried by said retracting means to release the latter from control of the dogging means.
8. In a door lock, a bolt, bolt retracting means, means within the door manually movable into engagement with said bolt retracting means to prevent the retraction of the bolt by the retracting means, while not interfering with the independent movement of said bolt, and key controlled means carried by the retracting means to free the latter from control of the preventing means.
9. In a door lock, a bolt, bolt operating hub, hub dogging means manually movable to engage said bolt operating hub, and key controlled means to move said dogging means out of operative position, said hub dogging means while in operative position permitting the independent retraction of said bolt.
- 10 10. In a door lock, a bolt, bolt retracting means, a dogging slide within the lock manually movable to position to dog the retracting means while permitting the free operation of said bolt and key controlled means carried by the retracting means to move the slide to inoperative position.
11. A door lock comprising a bolt, bolt retracting means including a rotatable spindle, a dogging slide manually movable into engagement with said retracting means to dog the retracting means while permitting the bolt to operate, and key controlled means within the spindle to actuate the slide.
12. In a door lock, a bolt, bolt operating mechanism including a member projecting from the door, a dogging slide manually movable to position to dog the operating mechanism while permitting the bolt to operate and key controlled means mounted 45 in said projecting member to move said slide in one direction into its inoperative position.
13. In a door lock, a bolt, bolt operating mechanism including a rotatable spindle, a dogging slide movable toward the spindle to dog the same against operation while permitting the bolt to operate, and key controlled means carried by the spindle to move the slide in the opposite direction.
14. In a door lock, a bolt, bolt operating mechanism including a rotatable spindle, a dogging slide mounted within the lock movable toward the spindle to dog the same against operation while permitting the bolt 50 to operate, and key controlled means carried by the spindle to move the slide in the opposite direction.
15. In a door lock, a support, a bolt slidably mounted upon said support, bolt operating mechanism including a member projecting from the door, a dogging slide 70 slidably mounted upon said support to dog the operating mechanism while permitting the bolt to operate, and key controlled means carried by the projecting member to actuate the dogging means.
16. In a door lock, a bolt, means to operate the bolt including inside and outside handles and a rotatable spindle connecting said handles, a manually operable dogging member movable from one side of the door 75 to dog the spindle against rotation while permitting the bolt to operate, and rotatable means extending through one of said handles to release the spindle from the dogging action of said dogging member.
17. In a door lock, a bolt, bolt operating mechanism including a rotatable stem secured to the lock, and an escutcheon plate rotatably mounted upon the stem and adapted to seat upon and be secured to the door.
18. In a door lock, a bolt, bolt operating mechanism including a spindle, a dogging member movable to position to dog the operating mechanism and provided with a part adapted to enter an opening in the spindle, and means engaging said part when within the opening to move the dogging member into inoperative position.
19. In a door lock, a bolt, bolt operating mechanism including a spindle, a dogging member movable to position to dog the operating mechanism and provided with a part adapted to enter an opening in the spindle, and key controlled means mounted within the spindle to move the dogging member 100 away from the spindle.
20. In a door lock, a bolt, bolt operating mechanism including a rotatable shell, a dogging member having a part adapted to be moved toward the shell and beyond the 110 periphery thereof, and means mounted in the shell to engage said part to move the dogging member away from the shell.
21. In a door lock, a bolt, bolt operating mechanism including a rotatable spindle 115 provided with an opening, a dogging member having a part adapted to enter said opening, and actuating means for the dogging member mounted in the spindle opposite the opening.
22. In a door lock, a bolt, bolt operating mechanism including a hollow spindle, dogging means for the operating mechanism having a part adapted to project into the spindle, and key controlled means carried by the spindle for actuating said dogging means including a cam member mounted in the spindle opposite the opening,

23. In a door lock, a bolt, bolt operating mechanism including a hollow spindle having an opening through the wall thereof, dogging means for the operating mechanism 5 having a part adapted to project into the spindle, and key controlled means carried by the spindle for actuating said dogging means including a cam member mounted in the spindle opposite the opening, and a lock 10 carried at the outer end of the spindle and provided with a key barrel connected to said cam mechanism.
24. In a door lock, a bolt, a bolt operating spindle projecting from the door, bolt operating spindle dogging means movable from the inside of the door and key controlled means carried by said spindle at the outside of the door to move said dogging means positively out of dogging engagement 15 with said operating spindle.
25. In a door lock, a bolt, operating means for the bolt, means movable from the inside of the door to dog the operating means while permitting the operation of the bolt, 20 and key controlled means carried by the operating means at the outside of the door to move the dogging means positively into an inoperative position.
26. In a door lock, a bolt, a bolt operating hub, means manually movable into dogging engagement with said hub to dog the hub against movement, a hub operating spindle at the outside of the door, and key controlled means carried by said spindle to 30 actuate the dogging means.
27. In a door lock, a bolt, a bolt operating hub, actuating means for the hub projecting from the door, a dogging slide having a part to engage the hub to dog the same against 40 movement and having an actuating finger, and means carried by said hub actuating means to engage said finger and actuate the slide.
28. In a vehicle door lock, a combination 45 of a lock case, a spring protracted latch bolt therein, a knob at the outside of the door, a bolt retracting member operable by said knob, means movable to engage said bolt retracting member to dog said bolt retracting member directly while permitting the incursion of the bolt, and key actuated means operable from the outside of the door through said knob for controlling said dogging means.
29. In a vehicle door lock, a case, a spring protracted latch bolt therein, an outer retracting knob, a retracting member in the case operable by said knob, means at the inside of the door movable into engagement 55 with said retracting member for dogging said retracting member independently of the bolt, and key controlled releasing means carried by said knob for said dogging means located at the outer side of the door.
30. In a vehicle door lock, a case, a spring 60 protracted latch bolt therein, an outer retracting knob, a retracting member operable by said knob, means movable from the inside of the door into engagement with said retracting member for dogging said retracting member independently of the bolt, and key controlled releasing means for said dogging means located at the outer side of the door within said knob.
31. In a vehicle door lock, a case, a spring 70 protracted latch bolt therein, a manually operable manipulating member for retracting said bolt from the outside of the door, means movable from the inside of the door into engagement with said manually operable manipulating means for dogging the operation of said manually operable manipulating means, and means comprising a key lock located in said manually operable manipulating member at the outside of the 75 door and cooperating with said dogging means substantially within the lock case for releasing said manipulating means so that it is free to operate.
32. A vehicle door lock comprising a 80 latch bolt, a handle for retracting the same from the outside of the door, manually operable means for dogging the handle when the door is open independently of the latch bolt whereby the door may be closed, and 85 key controlled mechanism at the outside of the door for undogging the handle, said mechanism including a rotatable member adapted to engage said dogging means and carried by said handle.
33. A vehicle door lock comprising a 90 latch bolt, a handle for retracting the same from the outside of the door, manually operable means for dogging the handle when the door is open without interfering with the closing of the door, and key controlled mechanism at the outside of the door for undogging the handle, said key controlled mechanism being located within said 95 handle and rotatable by a key.
34. A vehicle door lock comprising a 100 latch bolt, a handle for retracting the same from the outside of the door, manually movable means for dogging the handle when the door is open without interfering with the closing of the door, and key controlled mechanism at the outside of the door for undogging the handle, said key controlled mechanism being located within said handle, and said dogging mechanism including 105 a laterally movable manipulating element accessible at the inner face of the door to place the dogging means in operation and to release the same.
35. In a door lock, a bolt, means to operate the bolt including inside and outside operating members, and a rotatable member connecting said operating members, a dogging member to dog said rotatable member 115 against rotation while permitting the bolt 120
- 65 30. In a vehicle door lock, a case, a spring 125

to operate, means manually engageable for moving said dogging member into operative position and to release the same, and means extending through one of said operating members to positively release the rotatable member from the dogging action of said dogging member.

a dogging slide movable toward the spindle 10 to dog the same against operation and movable away from said spindle to release the same from the dogging action thereof, and means carried by the spindle to move the slide into spindle releasing position.

15

In witness whereof, I have hereunto set my hand on the 24th day of April, 1922.

ARTHUR E. WOODRUFF.

36. In a door lock, a bolt, a bolt operating mechanism including a rotatable spindle,
